INTERCHANGEABLE HEEL

Emil Christensen, Portland, Oreg.

Application October 23, 1933, Serial No. 694,746

2 Claims. (Cl. 36—36)

My invention relates to heel members for foot-wear and is preferably made of moulded rubber or substitute therefor. The object of my invention is to provide a heel member that provides no metal fastening on the wearing surface thereof, since such protruding metal surfaces are prone to scratch floors and the like. Another object of my invention is to provide a heel of the character indicated that may be readily replaced without the employment of a skilled artisan for such replacement. The third object of my invention is to provide a heel that is interchangeable between the right and left shoe of a pair, and therefore provides that the wear, ordinarily unequal at the extreme rear of the heel, may be equalized by changing from one shoe to another, of a pair, after some wear has taken place. A further object of my invention is to provide a heel of the character described in which the wearing portion at the extreme rear of the heel is substantially thicker than the balance of the heel to provide for the excess wear commonly found at this point. These and other objects that will be apparent from the following specification constitute the purpose of my present invention.

To accomplish these purposes, I make my new interchangeable heel in two pieces, one of which is permanently attached to the sole of a shoe in the proper place and which may be conveniently referred to as the "anchor". The other is arranged to lock firmly to the anchor and will be hereinafter referred to as the "heel".

My invention is illustrated in the accompanying drawing, in which,—

Fig. I is a plan view of the anchor;

Fig. II is a longitudinal section of Fig. I on the line II—II;

Fig. III is a cross-section of Fig. I on the line III—III;

Fig. IV is a plan view of Fig. VI showing the heel;

Fig. V is an elevation of Fig. IV in projection; and

Fig. VI shows a portion of a shoe in dotted outline, with both the anchor of the heel in place thereon, shown in longitudinal section in full lines, and, in dotted outline, an indication of how the heel is attached to the anchor.

The anchor will be designated by the numeral 8 and the heel by the numeral 9. They are both preferably manufactured from moulded vulcanized rubber or a substitute therefor, the anchor preferably being made of a suitable mixture and vulcanized somewhat harder than the heel, the

difference in quality being indicated by the difference in the section lines shown in the drawing.

The anchor is provided with an internally threaded opening, 10, and the heel is provided with an externally threaded projection, 11. These are so proportioned and designed that when the heel is applied reversely to the anchor, that is with the rear end forward, the two threaded portions, 10 and 11, will engage and a half turn of the heel with respect to the anchor will bring the two parts together as shown in Fig. VI, the rear end being sprung outwardly, permitted by its resilient qualities, as shown at 8a, and when the thread is completely home, the rear end portion represented by 8a will be released and will spring straight, as shown in Fig. V, and interlock with the anchor to prevent movement relative thereto unless it is purposely accomplished by springing the portion 8a back again to the position shown in Fig. VI, when it can be removed by reversing the operation described for attaching it. The anchor 8 is provided with an offset upwardly stepped portion 12 and the heel, 9, is provided with a correspondingly shaped upward projecting portion 8b to engage therewith and an interlocking lug 13 on the anchor engages with a recess, 14, moulded in the heel.

I do not wish to limit myself to the threaded means as shown for attaching the two parts together since a bayonet joint or an interrupted thread may be substituted, though I prefer the construction as shown. Also different forms of the locking device here represented by 13 and 14 may be substituted.

To use, the anchor will be firmly attached to the shoe by fastenings such as diagrammatically indicated at 14', passing through holes such as 15 moulded in the anchor, and this part may be considered permanent as long as the shoe lasts.

From time to time, as the heels wear, they may be quickly and easily renewed without the use of any tool and/or they may be interchanged from right to left if the wear, as is customary, wears off the outside rear portion of the heel. By so changing them, an increase in lasting qualities will be apparent.

It is a well known fact that the rubber heel of commerce is described as worn out when say 75% of its original structure is as good as new. With my new interchangeable heel the wearing portion, and substantially that only, is affected by wear and it can be removed and replaced without the employment of a skilled artisan in

a few seconds of time to completely renew the wearing surface of the heel.

Having thus fully disclosed my invention so that those familiar with the art to which it appertains can make and use it, what I claim as new and desire to secure by Letters Patent is:

1. In an interchangeable heel device for footwear, an anchor portion adapted to be permanently attached to a shoe, an internally threaded opening centrally disposed therein, an upwardly stepped portion rearwardly of the said opening, a lug extending partly across said stepped portion and a matching removable wearing surface of resilient material that is adapted to be screwed into and out of the recess and resiliently sprung

over and locked with said lug and said upwardly stepped portion.

2. A two-piece interchangeable heel for footwear comprising in combination an anchor portion adapted to be permanently attached to a shoe, a centrally disposed threaded opening in said anchor portion, an upwardly offset surface rearwardly of said opening, a locking lug extending partly across said offset surface and a removable wearing portion provided with matching surfaces that is adapted to screw into said recess and spring to locking position over the said offset.

EMIL CHRISTENSEN.
